OF DOVER, NEW HAMPSHIRE, A CORPORATION OF WEST VIRGINIA.

SHEET-DELIVERY MECHANISM.

No. 923,151.

Specification of Letters Patent.

Patented June 1, 1909.

Application filed February 19, 1907. Serial No. 358,248.

To all whom it may concern:

Be it known that I, EDMUND W. DEAN, residing at Dover, in the county of Strafford and State of New Hampshire, have invented 5 certain new and useful Improvements in Sheet-Delivery Mechanism, of which the following is a full, clear, and exact description, such as will enable others skilled in the art to which it appertains to make and use the 10 same.

This invention relates to the accumulation and delivery of sheets of paper and the like.

One of the objects thereof is to provide 15 efficient and practical means for accumulating sheets in condition for delivery.

Another object is to provide means of the above type adapted to accumulate any desired number of sheets without interfering 20 with or affecting the operation of the apparatus.

Another object is to provide means in connection with means of the first mentioned type adapted to insure a uniform disposition 25 of the sheets.

Other objects will be in part obvious and in part pointed out hereinafter.

The invention accordingly consists in the features of construction, combinations of 30 elements and arrangement of parts which will be exemplified in the construction hereinafter set forth, and the scope of the application of which will be indicated in the following claims.

35 The accompanying drawing is a diagrammatic view showing one of various possible embodiments of this invention.

In order to render clearer certain features 40 of this invention, it may here be noted that in connection with certain types of printing machinery a high speed of output is imperatively demanded. As an incident of this high speed, it is usually desirable to remove the sheets in large numbers, and thus means 45 are required for accumulating large piles of the sheets, which action in many types of apparatus in somewhat general use is precluded by reason of the accumulated sheets tending to interfere with the operation of the 50 machine. The above and other defects are

remedied in constructions of the nature of that hereinafter described.

Referring now to the accompanying drawing, there are shown feed rolls 1 adapted to feed a web 2 to a rotary cutter 3 coacting 55 with an abutment 4 and adapted to sever the web into sheets, which are guided to a sheet path 5. The tapes of this path are preferably driven at a speed somewhat higher than that of the feed rolls 1, the same 60 being accomplished by the gearing which is indicated throughout the drawing in dotted lines. The upper tapes 6 of sheet path 5 project considerably beyond the lower tapes 7, and the advancing sheet, being speeded 65 up and thus spaced from the following free edge of the web upon entering the sheet path, is thrown toward the upper tape by reason of its forward edge being curled upwardly by the disposition of the tape rollers 8 and 70 9 as shown in the drawing.

A suitable fly or set of arms 10 is normally held against a stop pin 11, as by the counter-balance 12, and is intermittently thrown downwardly, as by a pin 13 upon a gear 14, 75 thus striking each sheet away from the tapes 6 and throwing the same upon the pile 15 resting upon a support or table 16 positioned therebeneath.

The table 16 is mounted so as to be vertically movable, and is provided with a rack 17 intermeshing with a pinion 18 upon a shaft 19 which is driven through the worm 20 and wheel 21 from a shaft 22. The latter member is slowly rotated, as by the ratchet 80 wheel 23 and pawl 24 intermittently actuated from an adjustable crank 25 upon a shaft 26 driven by suitable gearing from the remainder of the machine. Thus upon each sheet being thrown toward the table 16, the latter is lowered throughout a predetermined distance so as to preserve a constant upper level of the pile 15 and hence render its relation to the remainder of the machine substantially uniform.

95 The edges of the sheets within pile 15 are justified, as by spring-retracted arms 27 intermittently thrown toward the pile by cams 28 driven as by the gearing indicated. In this manner the upper level of the pile is not 100

only maintained constant, but the entire number of sheets accumulated are maintained in exact registry one with another by the constant tapping exerted upon their edges at the upper portion of the pile, the arms 27 and associated parts not partaking of the dropping movement of the table 16.

The operation of the above described embodiment of my invention is substantially as follows: Assuming the parts to be in the relation shown, the web 2 is continuously fed by the rolls 1 and is cut into sheets of the desired length by the rotary cutter 3. Previous to the severing of the web, its forward edge has passed within the bite of the sheet path 5, and hence a slight tension is placed upon the web, which facilitates the cutting thereof and assures the snapping ahead of the severed sheet and its proper spacing from the forward free edge of the remainder of the web. The sheets are each in turn curled toward the upper tape 6 by reason of the disposition of the rollers 8 and 9 as above set forth, and this upwardly curled free edge tends to maintain the advancing sheet against the tape 6, from which it is thrown, as by the fly 10, upon the pile 15. As above set forth, the table is preferably lowered at a rate substantially equal to that at which the sheets accumulate thereon, and a constant upper level is thus maintained. The justifying arms or joggers 27 act, as above set forth, to maintain the sheets in proper registering position with relation one to another.

It will thus be seen that a pile of any desired height may be accumulated upon the table 16, and that the upper surface of this pile will maintain a constant relation to the fly 10 as well as the remaining parts of the machine. As the upper portion of the pile, moreover, is constantly tapped into the desired form, the entire pile, even when extending beneath these parts, will be in orderly condition and ready for removal and packing or any other desired disposition.

It will thus be seen that I have provided apparatus in which the objects of my invention are attained and the above enumerated advantages are, among others, present in a high degree.

The entire apparatus is of the simplest and most positively acting character, and is well adapted to withstand the high speed of running which is desirable in machinery of this general type.

Certain features herein shown and described are shown, described and claimed in my co-pending application Serial No. 303,359 filed February 28, 1906, and accordingly are not claimed herein.

As many changes could be made in the above construction and many apparently widely different embodiments of this invention could be made without departing from

the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:

1. In apparatus of the class described, in combination, a sheet path comprising a plurality of sets of tapes, the upper of said sets of tapes extending beyond the lower thereof, a vertically movable supporting table beneath the extended portion of said upper set of tapes, means adapted to throw sheets from said upper tapes downwardly upon said table, and means adapted automatically to drop said table as said sheets accumulate thereon, the tapes of said sheet path being so disposed as to incline the forward edge of a sheet therein toward the upper set of tapes.

2. In apparatus of the class described, in combination, a sheet path comprising a plurality of sets of tapes, the upper of said sets of tapes extending beyond the lower thereof, a vertically movable supporting table beneath the extended portion of said upper set of tapes, means adapted to throw sheets from said upper tapes downwardly upon said table, means adapted automatically to drop said table as said sheets accumulate thereon, and means associated with said sets of tapes to curl upward the forward edge of a sheet within said sheet path.

3. In apparatus of the class described, in combination, web-feeding means adapted to travel at a predetermined rate of speed, web-cutting means, a sheet path adapted to receive sheets from said cutting means, means driving said sheet path at a rate of speed higher than that of said web-feeding means, the upper tapes of said sheet path being extended beyond the lower tapes thereof, a vertically movable table positioned beneath the extended portion of said upper tapes, and means adapted to throw sheets downwardly from said upper tapes upon said table said sheet path being positioned to receive the forward edge of the web prior to the action of said cutting means and place the same under tension.

4. In apparatus of the class described, in combination, web-feeding means adapted to travel at a predetermined rate of speed, web-cutting means, a sheet path adapted to receive sheets from said cutting means, means driving said sheet path at a rate of

speed higher than that of said web-feeding means, the upper tapes of said sheet path being extended beyond the lower tapes thereof, a vertically movable table positioned beneath the extended portion of said upper tapes, means adapted to throw sheets downwardly from said upper tapes upon said table, and means adapted automatically to drop said table at such rate as to maintain the level of the uppermost sheet substan-

tially constant said sheet path being positioned to receive the forward edge of the web prior to the action of said cutting means and place the same under tension.

In testimony whereof I affix my signature, in the presence of two witnesses.

EDMUND W. DEAN.
